UNITED STATES PATENT OFFICE.

ROBERT B. GRIFFIN, OF NEW YORK, N. Y.

DESIGN FOR WALL-PAPER.

48,821.

Specification for Design.

Patented Apr. 4, 1916.

Application filed August 25, 1915. Serial No. 47,337. Term of patent 7 years.

To all whom it may concern:

Be it known that I, ROBERT B. GRIFFIN, a citizen of the United States, residing at New York, county of New York, and State of New York, have invented a new, original, and ornamental Design for Wall-Paper, of which the following is a specification, reference being had to the accompanying drawing, forming a part thereof.

The figure is a plan view of a piece of wall paper, illustrating my new design.

I claim:

The ornamental design for wall paper, substantially as shown.

ROBERT B. GRIFFIN.

Witnesses:

F. W. SCHAEFER,
A. KARPAY.
